UNITED STATES PATENT OFFICE.

HENRY J. ECKER, GEORGE F. ECKER, JOSEPH A. ECKER, AND FREDERICK ECKER, OF PHILADELPHIA, PENNSYLVANIA.

DESIGN FOR A BAR OF SOAP.

Specification forming part of Design No. **11,261**, dated June 24, 1879; application filed April 9, 1878.
[Term of patent 14 years.]

To all whom it may concern:

Be it known that we, HENRY J. ECKER, GEORGE F. ECKER, JOSEPH A. ECKER, and FREDERICK ECKER, trading as ECKER & Co., of Philadelphia, in the county of Philadelphia and State of Pennsylvania, have originated a Design for a Bar of Soap, of which the following is a full, clear, and exact description, reference being had to the accompanying drawing, making part of this specification.

A bar of soap is stamped, impressed, or molded into the appearance or similitude of three separate cakes of soap joined end to end. We usually stamp upon the bars, in addition, the words of our registered trademark, "Our Forefathers' Soap," and "One Foot;" but these words may be omitted or others used.

We hereby disclaim all title, claim, and right to the exclusive use of an "elongated bar of soap adapted, by reason of its having been pressed, stamped, or molded, to be broken into regular equal-sized flat cakes of soap, suitable for toilet use."

What we claim as our invention is—

A design for a bar of soap having the appearance and imitation of three perfect cakes of soap joined together endwise, or end to end, substantially as shown and described.

HENRY J. ECKER.
GEORGE F. ECKER.
JOS. A. ECKER.
F. ECKER.
